UNITED STATES PATENT OFFICE.

FRANK WALLACE LEIDECKER, OF MARIETTA, OHIO, ASSIGNOR TO
LEIDECKER GAUGE COMPANY, OF MARIETTA, OHIO.

GAGE-COCK.

No. 820,424.

Specification of Letters Patent.

Patented May 15, 1906.

Application filed August 18, 1905. Serial No. 274,759.

To all whom it may concern:

Be it known that I, FRANK WALLACE LEIDECKER, a citizen of the United States, residing at Marietta, in the county of Washington 5 and State of Ohio, have invented a new and useful Gage-Cock, of which the following is a specification.

This invention relates generally to gage-cocks, and more particularly to that class 10 employed on steam-boilers for ascertaining the level of the water therein.

The object of the invention is to simplify the construction and increase the efficiency and durability of such appliances.

15 With the above and other objects in view, as will appear as the nature of the invention is better understood, the same consists in the novel construction and combination of parts of a gage-cock for steam-boilers, as will be 20 hereinafter fully described and claimed.

25 In the accompanying drawings, forming a part of this specification, and in which like characters of reference indicate corresponding parts Figure 1 is a view in vertical longitudinal section through one form of the invention. Fig. 2 is a collective detail view of 30 parts of the valve mechanisms employed in connection with the appliance shown in Fig. 1. Fig. 3 is a vertical longitudinal section 35 through a modified form of the invention.

35 Referring to the drawings and to Figs. 1 and 2 thereof, 1 designates the body of the cock, which is provided with the usual exterior threads to engage a threaded opening in the boiler. At the inner or boiler-engaging 40 end of the body is arranged a cage 2, which is preferably integral with the body and is designed to house a ball-valve 3, that is adapted to engage a seat 4 when the main valve-stem 5 is removed for any purpose, thus to prevent 45 escape of steam and water through the cock. The outer or valve-stem-carrying end 6 of the body is externally threaded and is engaged by an internally-threaded cap 7, which constitutes 50 a stuffing-box, the cap being provided with a longitudinally-threaded orifice to receive the main valve-stem, which has combined with it, as usual, a handle or hand-wheel 8. The body is provided with a chamber 9, intersecting which is a passage-way 10 for the escape of water or steam from the boiler. Arranged within the chamber 9 and 55 bearing against the shoulder 11, formed thereby, is a reversible seat 12, which is en-

gaged by a ball-valve 13, that normally closes 55 exit through the passage-way and is held to its seat by the inner end of the main valve-stem, which is concaved to conform to the shape of the valve. The chamber also houses a cage 14, that carries spaced lugs 15, 60 the outer surfaces of which are flattened in order to present escape-passages 16 to permit the water to pass through a nipple 17, that is combined with the body of the cock in the usual manner. 65

Arranged within the passage-way is a twisted valve-stem 18, which is adapted to be rapidly turned or rotated by the passage of water or steam through the passage-way 10, and thus keep the latter free from any accumulation of sediments or the like. 70

One of the features of the present invention resides in dispensing with the ordinary stuffing-box, such as is generally employed, and in making the cap 7 subserve this function, to effect which the chamber in the cap that receives the terminal 6 is of considerable depth and houses the packing 19, which may be of any suitable substance suited for the purpose, preferably asbestos. When the cap 80 is seated, this packing is forced against the outer end 6 of the body, and thus compresses it around the main valve-stem and effects a steam and water tight juncture between the parts, that portion of the stem which engages 85 the packing being devoid of threads, so that no cutting of the packing will ensue. A portion also of the opening in the cap that receives the main valve-stem is also devoid of threads in order that the latter may have 90 requisite movement to permit the valve 13 to move away from the seat when the level of the water is to be ascertained. When the cap 19 is secured to its seat, the packing will engage with the cage 14, and thus hold it positively within the chamber. 95

In the form of the invention shown in Fig. 3 the only difference in construction is that the reversible valve-seat 12 and cage 14 are dispensed with, and the valve 16 engages a 100 seat 20, formed by the shoulder 21 of the chamber 9.

From the foregoing description, it will be seen that although the improvements herein defined are simple in character they will 105 be thoroughly effective for the purposes designed and will result in the provision of a gage-cock that will withstand wear and will

not be liable to become deranged from long-continued use.

Having thus described the invention, what is claimed is—

- 5 1. In a gage-cock, the combination with a body provided at one end with a chamber, of a seat arranged within the chamber, a ball-valve to engage the seat, a cage housing the ball-valve and carrying spaced lugs to permit 30 passage of liquid, a combined cap and stuffing-box carried by the body to hold the cage in position, and a valve-stem working within the stuffing-box and adapted to engage the valve.
- 10 2. In a gage-cock, the combination with a body provided at one end with a chamber, of a reversible seat arranged in the chamber, a ball-valve to engage the seat, a cage housing the ball-valve and carrying spaced lugs to 35 permit passage of liquid, a combined cap and stuffing-box carried by the body to hold the cage in position, and a valve-stem working within the stuffing-box and adapted to engage the valve.
- 15 3. In a gage-cock, the combination with a body provided at one end with a chamber, of a reversible seat arranged within the chamber, a ball-valve to engage the seat, a cage housing the ball-valve and carrying spaced lugs to 40 permit passage of liquid, a combined cap and stuffing-box carried by the body to hold the cage in position, and a valve-stem working within the stuffing-box and adapted to engage the valve.
- 20 4. In a gage-cock, the combination with a body provided at one end with a cage integral therewith and of less diameter than the body, of a ball-valve arranged within the cage, a twisted valve-stem arranged in the path of movement of the ball-valve, a second ball-valve arranged within the chamber at the other end of the body, a cage housed in the second valve and carrying lugs to permit 45 passage of liquid, a combined cap and stuffing-box carried by the body to hold the cage in position, and a valve-stem working within the stuffing-box.

ber, a ball-valve to engage the seat, a cage housing the valve and carrying lugs the exterior surfaces of which are flattened to permit passage of liquid, a combined cap and stuffing-box carried by the body for holding the cage in position, and a valve-stem working within the stuffing-box.

4. In a gage-cock, the combination with a body provided at one end with a cage integral therewith and of less diameter than the body, of a ball-valve arranged within the cage, a twisted valve-stem arranged in the path of movement of the ball-valve, a second ball-valve arranged within the chamber at the other end of the body, a cage housed in the second valve and carrying lugs to permit passage of liquid, a combined cap and stuffing-box carried by the body to hold the cage in position, and a valve-stem working within the stuffing-box.

In testimony that I claim the foregoing as my own I have hereto affixed my signature in the presence of two witnesses,

FRANK WALLACE LEIDECKER.
